UNITED STATES PATENT OFFICE.

FRANK A. SEIFERT, OF ST. LOUIS, MISSOURI, ASSIGNOR TO THE WESTERN STOVE MANUFACTURING COMPANY, OF SAME PLACE.

DESIGN FOR A COOKING-STOVE.

SPECIFICATION forming part of Design No. 22,608, dated July 11, 1893.

Application filed May 11, 1893. Serial No. 473,879. Term of patent 14 years.

To all whom it may concern:

Be it known that I, FRANK A. SEIFERT, of St. Louis, Missouri, have invented and produced a new and original Design for Cooking-Stoves, of which the following is a specification, reference being had to the accompanying drawing, in which the newly-designed stove is shown in perspective.

What chiefly characterizes my design is an ornamentation whose leading feature is apples, stems and leaves, and which appears more especially upon the oven and fire-place doors of the stove.

The design is more fully carried out when the base and other parts of the stove are embellished in an analogous manner. The ornamentation is more or less in relief. Upon the

oven-door, A, the apples, B, and the associated stems, C, blossoms D, and leaves, E, are arranged around a medallion F. Upon the fire-place door, G, apples, stems, and a blossom and leaf appear. A tracery of branches, H, II, having leaves, blossoms, and buds, I, is exhibited upon the base, J, of the stove, and upon the upright, K, at the rear side of the stove-top are apples, stems and leaves.

What I claim is—

The design for a cooking stove herein shown and described.

FRANK A. SEIFERT.
